UNITED STATES PATENT OFFICE.

JOHN SCHMADEL, OF CINCINNATI, OHIO.

TRUNK.

SPECIFICATION forming part of Letters Patent No. 450,533, dated April 14, 1891.

Application filed November 24, 1890. Serial No. 372,497. (No model.)

To all whom it may concern:

Be it known that I, JOHN SCHMADEL, a citizen of the United States, and a resident of Cincinnati, in the county of Hamilton and State of Ohio, have invented certain new and useful Improvements in Trunks, of which the following is a specification.

The object of my invention is to provide one or more trunk stay-straps which can be readily adjusted to any desired length or position upon the inside of the trunk, stretching across from side to side or from end to end, and which will form a separation between the articles packed in the trunk and at the same time hold them firmly in position.

Another object of my invention is to use this trunk-strap as a stay or strengthening-brace upon the inside.

The various features of my invention will be hereinafter described and claimed, reference being made to the accompanying drawings, making a part of this specification, in which—

Figure 1 is an inside elevation of one side of the trunk. Fig. 2 is a cross-section of the trunk with the lid removed. Fig. 3 is a sectional plan view of one of the stays attached in position. Fig. 4 is a plan view of the full-length stay.

In the drawings I have shown the stays as stretched from side to side upon the inside of the trunk; but they may be stretched from end to end, if preferred, and accomplish the same result.

1 represents the sides of the trunk, to which are secured a series of plates 2, which are preferably made of sheet metal, arched or curved transversely, as shown in Fig. 3, to provide a space between the arched or curved portion and the wall or side of the trunk to accommodate the heads of the stay-straps herein-after explained.

3 represents the nails or rivets for securing these plates to the trunk-frame.

4 represents a series of mortises pierced through the metal.

5 represents a flexible strap which is securely attached to the metallic plate 6, which has a fastening-head 7.

8 represents the neck of the head which rests in the mortise.

In Fig. 4 I have shown a strap made of sec-

tional pieces united by a buckle 9. One of these straps is pierced with a series of holes 10, so that any desired amount of tension may be employed or the strap drawn up for strengthening the trunk against inside strains. The form of fastening may be variously modified; but I prefer the T-headed form 7, which can be turned up edgewise and inserted 60 through any one of the mortises 4 and when turned around will securely hold it in position. This form of inside stay holds the articles firmly down to the bottom of the trunk, and a trunk part full can be shipped with the 65 same safety as if it were packed full. The said straps may be adjusted to hold any desired quantity of articles by means of the buckle 9. The plates 2 serve as stiffeners to the sides of the trunk, and when the straps 5 70 are connected to them upon both sides and strained they serve as inside stay-braces. It is obvious that these stays can be used with any desired size or style of trunk, and any desired number of stay-plates and any 75 number of fastening-points 4 may be employed.

Having described my invention, what I claim is—

1. A trunk having attached on its inside 80 the oppositely-arranged vertical plates, each having a series of mortises, in combination with a flexible stay-strap provided at each end with a head to engage the mortises for adjusting the strap vertically along the plates, substantially as described.

2. In a trunk, one or more series of plates 2, attached to each side of the frame thereof, provided with openings 4, in combination with a detachable flexible strap 5, secured to metallic plates 6, having the fastening-head 7, adapted to engage with the openings 4, substantially as herein described.

3. A trunk having attached on its inside 95 the oppositely-arranged vertical plates, each having a series of mortises, in combination with a lengthwise-adjustable stay-strap having its ends provided with heads to enter the mortises and engage the plates for adjusting the strap vertically along the latter, substantially as described.

4. A trunk-stay consisting of a set of plates arched or curved transversely and each having a series of mortises along its length, and

a flexible stay-strap having at each end a head to enter mortises and engage the plates, substantially as described.

5. A trunk-stay consisting of a set of plates arched or curved transversely and each having a series of mortises along its length, and a lengthwise-adjustable stay-strap having at each end a metallic plate provided with a

neck 8 and head 7, substantially as and for the purposes described.

In testimony whereof I have hereunto set my hand.

JOHN SCHMADEL.
